UNITED STATES PATENT OFFICE.

HOWARD H. GROSS, OF CHICAGO, ILLINOIS.

PANORAMA.

SPECIFICATION forming part of Letters Patent No. 624,479, dated May 9, 1899.

Application filed February 10, 1899. Serial No. 705,170. (No model.)

To all whom it may concern:

Be it known that I, HOWARD H. GROSS, a citizen of the United States, residing at Chicago, in the county of Cook and State of Illinois, have invented certain new and useful Improvements in Panoramas, of which the following is a specification, reference being had to the accompanying drawings.

My invention relates to improvements in panoramas, and particularly to those panoramas in which the scene to be viewed is painted upon the walls and roof of a circular building suitably arranged with a built-up foreground extending to and meeting the painting and provided with a point of observation which is so arranged as to form a part of the scene to be viewed, and still more particularly to panoramas in which a portion of the foreground is designed to represent water.

One of the objects of my invention is to provide means by which light effects, such as sunrise and sunset, may be arranged in a natural manner.

It has for a further object to provide mechanism by which the part of the panorama or part of the view which is designed to represent water may be given motion, so as to give the effect of moving waves; and it has for a further object to generally improve the structure and mechanism of such panoramas in details hereinafter pointed out.

That which I regard as new will be set forth in the claims.

In the drawings, Figure 1 is a horizontal cross-section. Fig. 2 is a vertical cross-section on lines 2 2 of Fig. 1; and Fig. 3 is an enlarged detail, being a view of a portion of the mechanism by which the movement of water is represented.

4 indicates the circular wall of the building, provided with the arched roof 5.

6 indicates the observation-platform, upon which the spectators stand to view the panorama and which is mounted upon a platform 7 and is approached by stairs 8, by which persons may mount to the platform 6 from below the supporting-platform 7. In the drawings I have shown the platform 7 and the observation-platform 6 as representing a ship and

parts thereof. It is obvious, however, that they may be made to represent some other natural

object, the essential being that the two platforms 6 and 7 should be built up so as to form to the observer standing upon the platform 6 some portion of the scene to be viewed. 55 Upon the side walls and ceiling of the building is painted the sky 9 of the picture.

10 indicates a canopy suspended from the roof 5 above the observation-platform 6, upon which lights 11 are mounted and connected 60 with any suitable apparatus for turning the lights off or on and varying the degree of light given thereby.

12 indicates a circular partition of canvas or other material suitable to have painted 65 upon it a portion of the scene. The circular partition 12 is concentric with the wall of the building and is set a suitable distance therefrom in order to receive behind it lights 13, which may be of various colors and are connected with any suitable apparatus for turning them up or down and varying to any desired degree the light given out thereby. The top of the circular partition 12 forms the horizon of the picture, and the partition has painted upon its inner surface such portion of the landscape as forms the horizon and the more distant parts of the landscape, which in Fig. 2 are represented as mountains, although it may represent any other natural objects. 80

14 indicates a second circular partition which is set inside the partition 12, concentric therewith and with a short space between them. Upon the inner surface of the circular partition, which is formed of any material 85 suitable to be painted upon, are painted such portions of the landscape as may be called the "middle distance," which in Fig. 2 is shown as being partly water and partly land.

15 indicates a series of thin boards bent in 90 the arcs of a circle, beveled at their upper edges and arranged along the lines of concentric circles having a common center below the point of observation. The boards 15 are supported at intervals upon posts 16, 95 which are driven into or otherwise secured to the floor of the building, and the posts which support the several boards are so arranged that the fixed post of every alternate board will come opposite the free space between the other boards. In other words, the boards are supported upon the fixed posts 16,

so that the supported portions of one are opposite to the unsupported portions of the other at a point approximately midway between its fixed supports.

- 5 17 indicates lugs which are secured to the rear surface of each of the curved boards 15 at a point midway between the fixed supports 16.
- 10 18 indicates wires, rods, or ropes, the inner ends of which are within the platform 7 in a suitable inclosure therein and which pass through and are secured to the lugs 17. It will be observed from what has been said that the several wires 18 are connected to every 15 alternate one of the boards 15 at the free portion thereof, so that a pull upon any one of the wires 18 will cause the several boards to which it is attached to move inwardly toward the center of the building a slight distance, and 20 when the wire is released the board will spring back to its original position. The inner surfaces of the boards 15 are painted to represent waves or ripples upon the water, and by the manipulation of the wires or rods 18 25 from within the platform 7, either by hand or by any suitable mechanism, the effect of moving waves is produced to the spectator standing upon the platform 6. In the drawings I have shown the boards 15 as surrounding 30 the platform 7 upon both sides, whereby the platform 7, which, as I have said, is built to represent a ship, would appear to be floating in the midst of the water, and such strips are so painted as to form with the platform 35 what may be called the "foreground" of the picture. I have also shown them as being so attached to the rods that the alternate ones move together. It is obvious, however, that these strips need not occupy the entire foreground 40 and completely surround the observation-platform and that they might be otherwise connected, so that groups of two or three only might move together, and I therefore do not wish to confine myself to the precise structure shown.

45 I have said above that the lights 11 and the lights 13 may be connected with any suitable apparatus for turning them up and down and varying to any desired degree the light given 50 out thereby. I have shown them in the drawings as electric lights connected with any suitable source of supply with the wires connecting them with the source of supply passing through a rheostat 19 and a suitable switchboard 55 20, which are located in any suitable position upon the platform 7, so that they may be controlled by an operator, and the lights, as above stated, may be of different colors in order to produce sunrise or sunset 60 effects. For instance, if it is desirable to make the scene apparently pass from night through sunrise to daylight the lights will be all turned out and gradually turned on by the manipulation of the switchboard through 65 the operation of the rheostat by the operator, using such colored lights as may be desirable. The lights which are in the portion of the

picture which represents the east will be first turned on gradually, one after the other, and then other lights in the panorama will be successively turned on, using such colors as may be desirable to produce the desired effect until, all the lights being lighted, the entire picture is illuminated, giving the effect, as said above, of passing from darkness through sunrise to 70 daylight. I do not, however, wish to confine myself to the use of electric lights and the precise apparatus shown, as it is obvious that the same effects might be produced by other forms of lights and other methods of turning 75 them on and off.

That which I claim as my invention, and desire to secure by Letters Patent, is—

1. In a panorama, the combination with a wall painted to represent the sky, of a partition parallel with said wall, set a distance therefrom, and painted to represent part of a landscape, lights arranged between said wall and said partition, and mechanism adapted to manipulate said lights, substantially as 85 described.

2. In a panorama, the combination with a wall painted to represent the sky, of a partition parallel with said wall, set a distance therefrom, and painted to represent the distant part of a landscape, and having its top 95 corresponding with the horizon-line of a landscape, lights arranged between said wall and said partition, and mechanism adapted to manipulate said lights, substantially as 100 described.

3. In a panorama, the combination with a circular wall having its inner surface painted to represent the sky, of a circular partition parallel with said wall, set a distance therefrom, and painted on its inner surface to represent the distant part of a landscape, and having its top corresponding with the horizon-line of the landscape, lights arranged between said wall and said partition, and mechanism adapted to manipulate said lights, substantially 105 as described.

4. In a panorama, the combination with a series of parallel flexible strips painted to represent waves upon their surfaces facing the foreground, and supported at intervals on fixed supports, of mechanism adapted to vibrate the free portions of said strips, substantially as described.

5. In a panorama, the combination with a 120 series of parallel flexible strips painted to represent waves on their surfaces facing the foreground, and supported at intervals on fixed supports so that the fixed supports of certain of said strips will come opposite the free portions of others of said strips, of mechanism adapted to vibrate the free portions of said strips, substantially as described.

6. In a panorama, the combination with a 130 series of parallel flexible strips painted to represent waves on their surfaces facing the foreground, and supported at intervals on fixed supports so that the fixed supports of every alternate strip will come opposite the free por-

tions of the adjacent strips, of mechanism adapted to vibrate the free portions of said strips, substantially as described.

7. In a panorama, the combination with a series of parallel flexible curved strips painted to represent waves on their surfaces facing the foreground, and supported at intervals on fixed supports so that the fixed supports of every alternate strip will come opposite the free portions of the adjacent strips, of mechanism adapted to vibrate the free portions of said strips, substantially as described.

8. In a panorama, the combination with a circular building painted upon its inner wall to represent features of a landscape, of a series of parallel concentric circular strips painted upon their inner surfaces to represent waves, and supported at intervals upon fixed supports, of mechanism adapted to vibrate the free portions of two or more of said strips simultaneously, substantially as described.

9. In a panorama, the combination with a circular building painted upon its inner wall to represent features of a landscape, of a series of parallel concentric circular strips paint-

ed upon their inner surfaces to represent waves and supported at intervals upon fixed supports so that the fixed supports of certain of said strips will come opposite the free portion of others of said strips, and mechanism adapted to vibrate simultaneously the strips whose free portions correspond with one another, substantially as described.

10. In a panorama, the combination with a circular building painted upon its inner wall to represent features of a landscape, of a series of parallel concentric circular strips painted upon their inner surfaces to represent waves, and supported at intervals on fixed supports so that the fixed supports of alternate strips will come opposite the free portions of the adjacent strips, and mechanism adapted to vibrate simultaneously the free portions of alternate strips, substantially as described.
